UNITED STATES PATENT OFFICE.

ROBERT D. KINYON, OF CHICAGO, ILLINOIS.

BARREL-FORMING MACHINE.

1,004,540.

Specification of Letters Patent. Patented Sept. 26, 1911.

Application filed January 12, 1911. Serial No. 602,367.

To all whom it may concern:

Be it known that I, ROBERT D. KINYON, a citizen of the United States, residing at Chicago, in the county of Cook and State of Illinois, have invented certain new and useful Improvements in Barrel-Forming Machines, of which the following is a specification.

My invention relates to barrel forming machines and has special reference to a machine for bringing the staves into the form to be assumed by the finished barrel.

I am aware that barrel forming machines have been used previously, but these are open to many objections on account of the difficulty of operation. The usual type of machine consists of a cable which surrounds the barrel and is operated by means of a power windlass. By means of such a machine it is very difficult to apply exactly the correct amount of pressure and also to keep the barrel staves in proper alignment.

In my improved machine the staves are preferably first steamed in order to render them pliable and their lower ends then placed in a retaining frame. The machine is then started and circular formers, moving toward each other from opposite sides of the barrel, are brought into contact with these staves, thereby keeping them in proper alignment and forcing them into the proper positions. My machine is also, in its preferred form, provided with a spring member which comes in contact with the center or bilge of the barrel. The formers which come in contact with the staves are preferably operated by means of sliding bars actuated by suitable gearing connected with racks and pinions. These and other advantages of my invention will be more readily understood by reference to the accompanying drawings in which:

Figure 1 is a plan of my barrel forming machine. Fig. 2 is a side elevation of the machine shown in Fig. 1. Fig. 3 is a fragmentary vertical section showing the mechanism directly associated with forming the barrel.

Resting on the supports 10, 11, and 12 are the longitudinal frame members 13 to which are attached the uprights 14 and 15, the cross member 16 extending between the two uprights 14 and being secured in position by the bolts 17. The longitudinal frame

members 13 are preferably channel-shaped being provided with grooves 18. Supported in suitable bearings is the shaft 19 having rigidly mounted near its ends the pinions 20. These pinions engage the racks 21 and 22 which are attached to the longitudinally sliding bars 23 and 24 so that on rotation of the shaft 19 the bars 23 and 24 will be moved in opposite directions. Also mounted on shaft 19 is the gear 25 which is in mesh with pinion 26 rigidly mounted on shaft 27, the ends of which are held in suitable bearings 28. Also mounted on shaft 27 is the gear 29 in mesh with the pinion 30 on shaft 31, the ends of which are mounted in bearings 32^a.

Loosely mounted on shaft 31 are the pulleys 32 and 33 which are rotated in opposite directions by means of suitable belts. Coöoperating with pulley 32 is the friction cone 34, and coöoperating with pulley 33 is the friction cone 35. The cone 34 is controlled by the clutch 36 by any of the well known methods, and the cone 35 is controlled by the clutch 37. In order to operate the clutches 36 and 37, a lever 38 is provided which is suitably connected with the handles 39 of the two clutch members 36 and 37. The lever 38 is pivoted to some suitable part of the left hand end of the machine shown in Figs. 1 and 2. The bracket 41 is secured to the bottom of one of the longitudinal frame members 13 by the pivot 40. The lever 38 terminates in the operating handle 42, and mounted on the lever is the roller 43 which is adapted to move within the slot 44 of the bracket 41. It will now be apparent that if the handle 42 is moved in a transverse direction, the lever 38 will serve to connect either the friction cone 35 with its corresponding pulley 33, or the friction cone 34 with its pulley 32. In the former case the shaft 31 will be rotated in one direction, and in the latter case in the opposite direction. As will be readily apparent to those skilled in the art, the rotary movement of the shaft 31 will be transmitted through the pinion 30, gear 29, pinion 26, and gear 25 to the shaft 19, thereby moving the sliding bar 23 in one direction or the other according to the direction of rotation of the shaft 31, and at the same time moving the sliding bar 24 in the opposite direction. On the other ends of the sliding bars 23

is mounted the cross member 45 which as clearly shown in Fig. 1 is in the form of an arc through most of its extent.

The upright supports 47 are secured to the right hand ends of the sliding bars 24. To the upper ends of these supports is bolted the cross member 48 similar to the cross member 45 but curved in the opposite direction. A controlling rod 49 is attached 10 to one of the bars 24, as shown in Figs. 1 and 2.

Attached to the cross member 45 are the brackets 50, these being secured to the member 45 near their central portions by means 15 of the extensions 51. These brackets are preferably inclined, as shown in Figs. 2 and 3. To the upper ends of brackets 51 is secured the curved forming member 52 by means of the rivets or bolts 53. To the 20 lower end of the brackets 50 is secured the semi-circular member 54, the position of which may be regulated by adjustment of the screws 54^a. Similar brackets 50 are attached to the cross member 48 by the extensions 25 51 and have secured to their upper ends the forming member 52, and to their lower ends a circular member 54.

Pivottally mounted on the ends of the forming members 52 are the movable forming members 55 which have the slots 56. Mounted on the cross members 45 and 48 are the guide bolts 57 which are placed in the slots 56 and serve to direct the movement 30 of the movable forming members 55 in a manner which will be described hereafter.

Extending through the members 54 are the pins 58 having on their ends the nuts 59. These bolts on their inner ends are 40 provided with clamps 60 retaining the spring formers 61. Between the clamps 60 and the inner edges of the members 54 are mounted the springs 62 surrounding the pins 58. The spring formers 61 have the 45 straight portions 63 which extend through the apertured brackets 64 mounted on the members 54. The apertures through these brackets are preferably of somewhat larger diameter than the diameter of the spring formers 61 in order to take care of slight 50 lateral movement as will be explained hereafter.

Between the supports 11 and 12 I place the stand 65 through the center of which is 55 the threaded aperture 66. Within this aperture the screw 67 is adapted to operate. The screw 67 is provided with the shoulder 68 above which is placed the compression spring 69. Between compression spring 69 and the head 70 of the screw 67, is placed 60 the base 71 preferably consisting of two plates 71^a and 71^b, the latter of smaller diameter than the former. Attached to the base 71 are the upright brackets 73 within 65 which is supported near their upper ends

the metallic ring or truss hoop 74. It will be evident that by turning the screw 67 the position of the base 71 may be elevated or depressed as desired. Just inside of the brackets 73 is placed the removable truss 70 hoop 72, between which and the plate 71^b is formed the annular groove 72^a.

Having thus described the construction of my machine, its operation may now be understood. After the barrel staves 75 75 have been steamed in order to render them pliable without breaking, their lower ends are placed within the annular groove 72^a in the base 71 and the staves occupy the positions shown in Fig. 2. The handle 42 is 80 now moved inwardly so that one of the friction cones 34 engages its corresponding pulley 32, and the pinion 20 is rotated in the direction shown by the arrow in Fig. 2. As a result the bar 23 is moved toward the 85 staves 75 and the bar 24 is moved in the opposite direction. This results in carrying both cross members 45 and 48 and their associated parts toward the barrel staves. The bilge of the barrel is engaged by the 90 spring formers 62 which conform to the shape of the barrel by outward pressure of the spring-controlled pins 58, the straight ends 63 of these spring formers meanwhile passing through the apertures of the 95 brackets 64. At the same time it will be clear that the formers 52 are brought toward the barrel and the movable forming members 55 are gradually moved inwardly by the guide bolts 57 operating within the 100 slots 56. In this way the staves are gradually forced into the positions shown in Fig. 3, and the barrel attains its finished shape. On the controlling rod 49 are mounted the collars 76 and 77 which are adapted to engage the angle iron 78 which is mounted on the bracket 41, the rod 49 passing through a suitable aperture in the angle iron 78. It will be apparent that as the sliding bars 24 move to the left, as indicated in the 105 drawings, the collar 76 will engage the angle iron 78 and the bracket 41 will be carried toward the left. The inner edge of the slot 44 will engage the roller 43 and the lever 38 will thus be moved outwardly, thereby disengaging the friction cone 34 from its pulley 32 when the formers have reached the position in which the barrel attains its final finished shape. In order to release the formers from the barrel, the handle 42 110 is moved still farther in an outward direction causing the cone 35 to engage the pulley 33 and the pinion 20 is rotated in the opposite direction from that shown by the arrow in Fig. 2. In this way the sliding bars 23 are moved to the left and the sliding bars 24 to the right until the collar 77 engages the angle iron 78, thereby moving the bracket 41 to the right and causing the outer edge of the slot 44 to engage 115 120 125 130

the roller 43. Such engagement causes the lever 38 to be gradually moved inwardly until the cone 35 is disengaged from the pulley 33, the operation of the machine thereby being stopped. When the staves have been brought into the form of the finished barrel, a temporary truss hoop may be applied to the top of the barrel. When the formers have been released from the barrel, the latter carrying with it the truss hoop 72 to hold the barrel in its proper form may then readily be removed from the machine another truss hoop 72 is placed within the brackets 73 and new staves are placed in position.

The spring 69, above-mentioned, is provided for the purpose of giving the barrel a resilient support while it is being formed.

It will be apparent to those skilled in the art that many changes could be made in the detailed construction of the machine which I have described without departing from the spirit and scope of my invention.

What I claim is:

1. In a barrel forming machine, the combination of means for resiliently supporting the ends of the barrel staves, a pair of formers located on opposite sides of the barrel to be formed from said staves and outside of the latter, and means for moving one of said formers toward the other, whereby the staves will be carried inwardly and the barrel formed, substantially as described.

2. In a barrel forming machine, the combination of resilient means for supporting the ends of the barrel staves, means for adjusting the position of said supporting means, a pair of formers located on opposite sides of the barrel to be formed from said staves and outside of the latter, and means for moving one of said formers toward the other whereby the staves will be carried inwardly and the barrel formed, substantially as described.

3. In a barrel forming machine, the combination of a movable bracket, a yieldable former adapted to engage the outer surfaces of the staves from which the barrel is to be formed, and spring-controlled means for attaching said former to said bracket, whereby on actuation of the latter said spring-controlled means will cause the former to conform to the shape of the barrel formed from said staves, substantially as described.

4. In a barrel forming machine, the combination of a pair of brackets, means for moving said brackets toward each other, a pair of spring formers adapted to engage the outer surfaces of the staves from which the barrel is to be formed, and a plurality of spring-controlled means for attaching each of said formers to its corresponding bracket, whereby said spring controlled

means will cause each former to conform to the shape of the barrel being formed, substantially as described.

5. In a barrel forming machine, the combination of means for supporting the ends of the barrel staves, a pair of brackets located on opposite sides of the barrel to be formed, means for simultaneously moving said brackets toward each other, a principal former attached to each of said brackets and adapted to engage the outer surfaces of the staves near their ends, a pair of auxiliary spring formers, spring-controlled means for attaching each of said auxiliary formers to one of said brackets, and means for preventing lateral spreading of the ends of said formers, whereby on movement of said brackets toward each other the staves will be concentrically brought inwardly and the barrel formed, substantially as described.

6. In a barrel forming machine, the combination of means for supporting the ends of the barrel staves, a former for engaging the outer surfaces of a portion of said staves, a slotted movable member pivoted to said former, and means engaging said slot whereby when said former is moved toward the central axis of the barrel to be formed said movable forming members will be laterally forced inwardly, substantially as described.

7. In a barrel forming machine, the combination of a pair of formers located on opposite sides of the barrel to be formed, means for moving one of said formers toward the other, a movable slotted forming member pivoted to each of said formers, and means on each former for engaging the slot of the movable member pivoted to the other former whereby said movable forming members will be guided inwardly toward the central axis of the barrel when one of said formers is moved toward the other, thereby carrying the staves inwardly and forming the barrel, substantially as described.

8. In a barrel forming machine, the combination of means for supporting the ends of the barrel staves, a pair of brackets located on opposite sides of the barrel to be formed, means for simultaneously moving said brackets toward each other, a principal former mounted on each of said brackets and adapted to engage the outer surfaces of said staves near their ends, a movable forming member pivotally attached to each of said principal formers, means for guiding said movable forming members inwardly when said brackets are moved toward each other, a pair of spring formers adapted to engage said staves near their central portions, means for resiliently attaching each of said spring formers to one of said brackets, and means for preventing outward

movement of the ends of said spring formers, whereby on movement of said brackets toward each other the staves are concentrically forced inwardly and the barrel formed, substantially as described.

9. In a barrel forming machine, the combination of means for resiliently supporting the ends of the barrel staves, means for adjusting said supporting means, and means for bringing said staves concentrically inwardly toward each other, whereby the barrel is formed, substantially as described.

10. In a barrel forming machine, the combination of a movable bracket, a yieldable

former adapted to engage the outer surfaces of the staves from which the barrel is to be formed, spring-controlled means for attaching said former to said bracket, whereby on actuation of the latter the former will conform to the shape of the barrel formed from said staves, and means for preventing the lateral spread of the ends of said former, substantially as described. 15 20
